attorney

UNITED STATES PATENT OFFICE.

CHESTER H. TEEGARDEN, OF WASHINGTON, DISTRICT OF COLUMBIA.

TELEGRAPH RELAY.

Application filed September 25, 1918. Serial No. 255,610.

To all whom it may concern:

Be it known that I, CHESTER H. TEEGARDEN, a citizen of the United States, and a resident of Washington, in the District of Columbia, have invented certain new and useful Improvements in Telegraph Relays, of which the following is a specification.

My invention relates to relays and in particular to that type of relays used in telegraphy. The principal objects of my invention are the provisions of a polarized relay which is biased to mid-position without necessitating an increase in the force required to operate the relay, the use in such a relay of abutting contacts which are closed under pressure and yet do not necessitate an increase in the operating force, the use of the biasing means as contact means, and the provision of means whereby said biasing means may be rendered ineffective so that the armature will remain in that extreme position to which it has been actuated. My relay is particularly of use in connection with my method of receiving telegraph signals which I have described in copending application, Serial No. 253,309, filed September 9, 1918.

In the drawings, Figure 1 represents a plan view of my relay, Figure 2 represents a section on the line 2—2 of Figure 1, and Figure 3 represents a side view of my relay with the front coils removed.

In its preferred embodiment my relay is provided with four coils, 1, 2, 3 and 4. Coils 1 and 2 are mounted on a cross-arm 5 by means of screws 6 and this cross-arm 5 is supported by a rack member 7 which fits within a recess in the post 8 and is reciprocated by means of the screw 9. The coils 3 and 4 are similarly mounted on an arm 10 supported by a rack member 11, which is received in a recess in post 12, and is operated by a screw 13. The posts 8 and 12 are secured to a base 53, of suitable material preferably insulation. It will be apparent that the screws 9 and 13 acting on the rack members 7 and 11 serve to reciprocate the coils so as to vary the spacing between the respective cores. Also mounted upon the base 53 are the supports 14 and 15 each carrying a bracket 16 in which is journaled one end of the armature 17. This armature con-

sists essentially of a long shaft like part 18, extending between the two bars 16, and three tongues 19, 20, and 21, extending upwardly 55 from the part 18.

The tongue 19 extends between the cores of the coils 1 and 3, while the tongue 21 extends between the cores of coils 2 and 4 and these tongues are adapted to swing on the 60 trunnions 16 between the coils 1 and 2 on the one side and the coils 3 and 4 on the other side.

The tongue 20 is provided with contact 65 22 extending through the tongue and secured in place by means of a set screw 23. This contact is adapted to engage, in the two extreme positions of the armature, with the contacts 24 and 25 which are in the form of screws provided with contact 70 points 26, threaded surfaces 27 and heads 28. The threaded surfaces 27 cooperates with threads in the apertures 29 in the supports 30 and 31. These two supports 30 and 31 are carried by the base 53 in such manner 75 as to be insulated from the supports 14 and 15.

Also carried by the supports 30 and 31 are brackets 32 and 33 which are practically identical. These brackets are insulated from the supports 30 and 31, and are provided with apertures 34 through which the screws 24 and 25 pass without contact. The bracket 32 is provided with a contact spring 35 supported from slot 37 in the 80 bracket. The tension on the spring is regulated by means of set screws 39 and the forward movement of the spring is limited by the shoulder 41 on the adjustable stop 45. The tension means 39 and stop 45 are both 85 carried by bracket 32. The bracket 33 is similarly provided with contact spring 36 supported in slot 38 and tensioned by set screw 40 and limited in its forward motion by the shoulder 42 of stop member 46 and the set screw 40 and the stop member 46 are similarly carried on bracket 33. Carried by the tongue 20 but insulated therefrom by means of tube 47 is the contact plug 48 so positioned as to engage the contact springs 90 35 and 36. When the armature 17 and the tongue 20 are in mid-position and the stop members 45 and 46 are properly adjusted the contact plug 48 is of such length as to 95 100

bridge the gap between spring contacts 35 and 36. Upon motion of the armature in either direction the contact 48 will disengage the opposite spring contact and thus 5 open the circuit between the two spring contacts. Upon this same motion the contact plug 22 will engage the one or the other of the contacts 24 or 25.

Carried by the bracket 32 is an extension 10 49 in which is supported shaft 50 carrying at its outer end a head 51 and at its inner end a cam 52. This cam is positioned between the two contact springs 35 and 36 and is of sufficient size in one direction to hold 15 these springs back from engagement with the stops 41 and 42 and prevent the contact 48 from bridging the two spring contacts 35 and 36. This cam 52 is of insulating material.

20 It will be apparent from the above description that normally the contact 48 bridges the spring contacts 35 and 36 and that this circuit is broken by movement of the armature 17 in either direction and by 25 rotation of the handle 51 to cause the cam 52 to retract the contact springs 35 and 36. It will further be apparent that normally no circuit is completed through contacts 24 and 25 but that a circuit is completed from one 30 or the other of these contacts upon the movement of the armature 17 in either direction to cause the plug 22 to engage the corresponding contact 24 or 25.

35 Mounted in the base 53 of my relay is a polarizing means for polarizing the armature 17. Inasmuch as I may employ any suitable polarizing means I have deemed it unnecessary to disclose any means in the drawing. I may state however that I preferably employ horse-shoe magnets, extending 40 in opposite directions from a line beneath the armature 17 and with their like poles together. I may also add that the coils 1, 2, 3 and 4 are so wound that when the flux in 45 coils 1 and 3 flow to the right that in coils 2 and 4 will flow to the left thus causing the flux to flow in a circuit through the four coils and the end bars 5 and 10. It will be apparent from the construction above described 50 that when the current flows through these coils in one direction it will cause movement of the armature in one direction and that a current through the coils in the reverse direction will cause movement of the armature in the reverse direction, and that 55 each movement will cause contact 22 to engage either contact 24 or 25 and also cause contact 28 to disengage either contact 36 or contact 35.

60 A special feature of my invention is the adjustment of tension in spring contacts 35 and 36. As is well known, in a biased relay the force required to move an armature from one position to the other must include a force 65 necessary to pull the biased armature away

from the cores toward which it lies. I provide this force in the springs 35 and 36 and adjust the tension of these springs so that they are sufficient to cause such breaking of the armature from the cores. By this 70 means I provide a relay wherein it is no longer necessary for the actuated force to overcome this magnetic stick and accordingly I thus offset the increase in force required to move the armature against the action of 75 one of the springs 35 or 36. In other words, I utilize the springs 35 and 36 to overcome the magnetic stick and accordingly I am enabled to permit the actuating force to remain at the same value. By this means I 80 produce a relay which is biased to mid-position without necessitating an increase in the operating force. Another feature of my invention is the production of an abutting contact closed under pressure without increase of the operating force and, inasmuch as these contacts are the same parts which are used to return the armature to mid-position, I accomplish this result by the same method of properly tensioning the springs 85 35 and 36. A further advantage of my new 90 relay is in the use of the same parts to produce the tension to return the armature to mid-position and to act as a contact. Another advantage of my relay arises from the 95 provision of the cam 52 whereby I may at will convert my relay into an ordinary polarized relay wherein the armature remains in either position to which it has been actuated.

100 I am aware that my relay may be operated and used without the contact 22, 24, and 25. I am also aware that other forms of spring contacts could be used in place of the contact 35 and 36, and by the term spring contact or resilient contact I include such substitutions as may properly be included within the scope of my invention. I am particularly aware, however, that one form of that resilient contact might be a pivoted contact biased to position by means of some sort of additional spring member. I am aware of other changes and modifications which might be made in my relay and which would secure one or more of the objects of my invention 110 and all such changes and modifications which come within the scope of the appended claims I deem to be a part of my invention.

115 Having described my invention in its preferred embodiment, I claim:

120 1. In a relay, a movable member, a pair of opposed biasing members for returning said movable member to mid-position, and common means for rendering said biasing means ineffective.

125 2. In a relay, a movable member, a pair of opposed spring pressed members for returning said movable member to mid-position, and means for simultaneously rendering said spring pressed members ineffective.

3. In a relay, a movable contact, spring arms supported in proximity to said movable contact adapted to impart movement in opposite directions to the same, adjusting screws engageable with the spring arms to vary their tension and pressure upon the movable contact, other screws engageable with the free extremities of said spring arms

for limiting adjustment of the spring arms, contacts on the spring arms, engageable with the movable contact, and means for rendering the second mentioned contacts ineffective.

In testimony whereof I affix my signature.

CHESTER H. TEEGARDEN.
